UNITED STATES PATENT OFFICE.

REINHARDT DAAE, OF PITTSBURGH, PENNSYLVANIA.

GAS PRODUCER.

Application filed January 7, 1920. Serial No. 349,863.

To all whom it may concern:

Be it known that I, REINHARDT DAAE, a citizen of the United States, residing at Pittsburgh, Allegheny County, Pennsylvania, have invented a new and useful Improvement in Gas Producers, of which the following is a full, clear, and exact description.

The present invention relates to gas producers and has for its principal object a novel form of poker and means for actuating the same.

Another object of the present invention is to provide a poker with means for actuating the same in such manner that it will move in overlapping spirals during the operation of the producer to effect a maximum poking action uniformly throughout the fuel bed.

Still another object of the invention is to provide means for alternately reversing the direction of travel of the poker.

An additional object of the invention is to combine with the poker a plow adapted to smooth the fuel bed after it has been subjected to the action of the poker and fill all of the openings formed therein.

A further object of the present invention is to provide means controlled by the position of the plow for regulating the rate of fuel fed to the producer, for maintaining a uniform fuel level therein.

A still further object of the invention is to provide an improved feed operating in a water seal and adapted to be automatically disconnected from its driving means under conditions tending to clog or break the same.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a vertical sectional view through the upper portion of a producer constructed in accordance with my invention.

Figure 2 is a vertical sectional view through a portion of the producer at substantially right angles to the section shown in Figure 1, part of the mechanism being omitted for sake of clearness.

Figure 3 is a cross-sectional view, partly broken away, on the line III—III of Figure 1.

Figure 4 is an enlarged detail view partly in section illustrating the feed controlling mechanism.

Figure 5 is a side view of the construction illustrated in Figure 4.

Figure 6 is an enlarged detail sectional view of the lower feed casing, taken on the line VI—VI of Figure 7.

Figure 7 is a side view partly in section of a portion of the fuel feed.

Figure 8 is an enlarged detail sectional view of the reversing mechanism for the poker.

Figure 9 is a side view of the construction illustrated in Figure 8, and

Figure 10 is a diagrammatic view representing the travel of the poker.

It has heretofore been proposed to provide gas producers with a poker rotatably carried by the cover and adapted, during the production of a relative movement between the cover and the body of the producer, to be rotated about its own axis. This causes the poker to travel in a series of circles which results in a maximum poking action adjacent the central and outer portions of the producer, and a minimum action in the intermediate portions of the fuel bed. It is the object of the present invention to provide means for uniformly poking the entire fuel bed during the operation of the producer.

In the drawings I have illustrated a producer which may be of any desired construction, preferably comprising a body portion 2 supported in any suitable manner, and provided with a gas outlet 4. Carried by the producer body is a channel-shaped member 5 forming a water seal for the depending angular flange 6 of the cover 7. According to the present invention, the entire feeding and poking mechanisms are carried by the cover, thereby making it essential that a relative movement between the body portion and the cover be produced. In the drawings the body of the producer is represented as being stationary and the cover as being the driven member, although it will be apparent that this condition may be changed if found desirable. For rotating the cover, it is provided with a projecting rim 8 having a series of teeth 9 formed in its outer periphery to constitute a ring gear. Meshing

with this gear is a driving gear 10 carried by the shaft 11 driven from any desired source, not shown.

Co-operating with the ring gear to maintain the cover in its proper position are anti-friction rollers 12 and 14, respectively, effective at substantially right angles to each other for preventing lateral movement of the cover and supporting the same for rotation.

10 The cover is formed with a feed opening 15 therethrough, located at one side of the center of rotation of the cover and adapted to receive fuel from the casing 16 having a pivotal mounting 17 on the producer cover.

15 Pivoted supported by the casing 16 is a sliding trap cut-off 18 adapted during the operation of the producer to receive a predetermined amount of fuel through the chute 19 co-operating with the hopper 20.

20 For operating the fuel feed, the cover is provided with a transverse shaft 21 carrying a bevel gear 22 at its outer end meshing with a gear 24 formed on the channel member 5. Due to this construction as the cover

25 is rotated, rotation will be imparted to the shaft 21 and thence through the bevel gear 25 to the bevel gear 26 on the stub shaft 27. The opposite end of the stub shaft carries a pinion gear 28 meshing with a similar gear

30 29 on the shaft 30, carrying an adjustable eccentric 31 for the pitman 32 having a connection 34 with one side of the casing 16. From the foregoing it will be apparent that as the cover is rotated, the casing 16 will be 35 oscillated across the feed opening 15 in the cover and about its pivotal mounting 17. By changing the adjustment 31, the amount of travel of the casing may be regulated at will.

40 The fuel for the casing 16 is supplied by the sliding trap cut-off 18, as before described. For actuating this cut-off the shaft 21 may be provided with a supplemental bevel gear 35 meshing with the gear 36 on

45 the shaft 37. This shaft also preferably carries an adjustable eccentric 38 for the pitman 39, one end of which has a pin and slot connection 40 with the pivoted lever 41. The upper end of the lever 41 is bifurcated

50 and carries a pin 42 adapted to engage the notch 44 in the lever 45 pivotally connected at 46 with the sliding trap cut-off. During normal operation of the cover, the sliding cut-off will be actuated by the mechanism de-

55 scribed for frictionally transferring fuel from the chute 19 to the casing 16, from which casing it is, in turn, fed into the producer. The stroke of the sliding cut-off is preferably such that the opening or pocket 60 therein is never brought into complete alignment with the chute, thus insuring the transfer of the fuel frictionally by the upper surface of the cut-off.

For preventing clogging and consequent 65 breaking of the apparatus, a yoke 47 is piv-

otally connected to the opposite sides of the chute 19 and carries a roller 48 adapted to co-operate with the sliding trap cut-off. Projecting downwardly from the forward portion of the yoke is an arm 49 adapted to 70 lie under the angular portion 50 of the lever 45. If any of the fuel projects above the pocket in the trap cut-off, it will elevate the yoke 47 through the roller 48, and thereby disengage the lever 45 from its operating 75 lever 41. As soon as the material is properly positioned within the cut-off, the parts will resume their normal positions and fuel will again be automatically fed to the producer. 80

To insure rotation of the chute 19 with the casing 16, there may be provided connecting pins or bars 51. Also the casing 16 may have a portion 52 of one of its walls inclined to facilitate the feed of fuel through 85 the cover opening, and may be provided with an adjustable gate 54 for assisting in the control of the feed.

The cover also carries a poker 55 and a plow 56 with mechanism for actuating the 90 same. The poker is preferably swingingly mounted in the cover, and provided with a segmental gear 57 by means of which it may be swung during rotation of the cover to cause the same to travel in a spiral. 95 Meshing with the gear 57 is a worm 58 on the shaft 59. This shaft is adapted to be driven in one direction from the shaft 21 by the gearing 60 and in the opposite direction by the gearing 61. Co-operating with 100 the gearing 60 and 61 is a clutch member 62 adapted to be moved into driving engagement with either set of gearing. The clutch member 62 is controlled by one end of the bell crank 64 having a pivotal mounting 65 105 on the producer cover, and having its opposite end 66 in engagement with the lever 67 having a pivotal mounting 68. The upper end of the lever 67 carries a weight 69, and this intermediate portion is provided with 110 an arcuate slot 70 through which the arm 66 passes. Projecting from one side of the lever 67 is an arm 71 adapted to be intermittently engaged during the operation of the producer by one of the pins 72 carried 115 by the poker 55. From the foregoing, it will be apparent that after the poker has been swung a predetermined distance about its axis in one direction, one of the pins 72 will engage the arm 71 and through the lever 120 67 and bell crank mechanism described, throw the clutch member into engagement with the other set of gearing, thereby changing the direction of movement of the poker. Due to the provision of the weight and the 125 slot, a snap action of the clutch member is insured. The gearing is preferably such that the direction of movement of the poker will be reversed once for every four complete revolutions of the cover, thereby caus- 130

ing the poker to travel in overlapping spirals 74, as illustrated more particularly in Figure 10. By changing the gearing ratio, however, the direction of travel of the poker may be automatically reversed sooner or later with respect to four or more complete revolutions of the cover, so that the spiral path, traversed by the poker, will be automatically varied. By bending the lower portion of the poker, as clearly indicated in Figure 2 of the drawings, there is exerted a continuous down pressure on the fuel bed during the operation of the producer, thereby tending to prevent objectionable opening up of the fuel bed. The gradual travel of a poker constructed in the manner described, has been found to produce a uniform poking action throughout the entire body of the fuel.

20 Co-operating with the poker 55 is a plow 56 which is preferably formed by two arms adapted to straddle the poker and connected by the intermediate transverse portion 56^a forming a presser foot riding over the fuel bed and filling the openings which may be formed by the poker. The plow is adapted to slide through a bushing in the cover in accordance with the level of the fuel within the producer. This movement of the plow is 25 utilized for regulating the rate or amount of fuel fed to the producer by means of a segmental projecting member 75 secured to the upper end of the plow. This member co-operates with one arm of a bell crank 30 lever 76, the opposite arm of which is connected by a link 77 with one arm of a similar bell crank 78. The other end of the bell crank 78 has an angular portion 79 provided with an opening 80 adapted to receive the arm 81 attached to the pitman 39 so that the position of the pin and slot connection with the lever 41 is automatically 35 changed, thereby changing the amount of travel of the sliding trap cut-off 18.

40 45 It will be apparent that the plow 56 is mounted to swing with the poker so that a predetermined relationship exists therebetween.

The advantages of the present invention 50 arise from a construction in which the poker is caused to travel in overlapping spirals so that the body of the fuel is uniformly poked.

55 A further advantage arises from the provision of a plow co-operating with the poker for filling openings formed in the fuel bed and at the same time controlling the amount of fuel fed to the producer.

60 A still further and important advantage of the present invention arises from the method of frictionally transferring fuel from the chute to the feed casing by limiting the travel of the sliding cut-off in such manner that the opening or pocket therein is never brought into complete alignment with 65 the chute.

The broad features relating to the producer construction and the method of feed are claimed in my copending application, Serial No. 334,913, filed November 1st, 1919.

I claim:

1. A gas producer having in combination a body portion, a cover, means for producing a relative rotational movement between the body portion and cover, a poker swingingly mounted on the cover, and means for swinging the poker about its axis, each complete swinging movement requiring at least one complete relative rotation between the cover and producer body substantially as described. 70

2. A gas producer having in combination a body portion, a cover, means for producing a relative movement between the body portion and cover, a poker swingingly mounted on the cover, and means for automatically swinging the poker in opposite directions about its longitudinal axis during such relative movement, substantially as described. 85

3. A gas producer having in combination a body portion, a cover, means for producing a relative movement between the body portion and cover, a poker swingingly mounted on the cover, means for swinging the poker in opposite directions about its longitudinal axis, and means for automatically reversing the direction of movement of the poker, substantially as described. 90

4. A gas producer having in combination a body portion, a cover, means for producing a relative movement between the body and cover, a poker having a portion adapted to project into the fuel bed within the producer, and means for swinging said poker about its longitudinal axis for causing said poker 100 to travel in substantially a complete spiral during each revolution between the body and cover substantially as described. 105

5. A gas producer having in combination a body portion, a cover, means for producing a relative movement between the body and cover, a poker having a portion adapted to project into the fuel bed within the producer, means for swinging said poker about its longitudinal axis for causing said poker 110 to travel in substantially a complete spiral during each revolution between the body and cover, and means for reversing the direction of travel of the poker, substantially as described. 115

6. A gas producer having a body, a cover, means for producing relative movement between the body and cover, a poker, means for actuating the same, and a plow co-operating therewith to smooth the fuel bed 120 after it has been subjected to the action of the poker, substantially as described. 125

7. A gas producer having, a body, a cover, means for producing relative movement between the body and cover, a poker, a plow 130

co-operating therewith, and means for swinging the poker and plow, substantially as described.

8. A gas producer having in combination a body portion, a cover, means for producing a relative movement between the body and cover, a poker swingingly mounted on the cover and having its lower portion bent to extend into the fuel bed within the producer, and means for swinging the poker about its axis, to cause said bent portion to always exert a compressing action on the fuel bed substantially as described.

9. A gas producer having a body, a cover, means for producing relative movement between the body and cover, means for feeding fuel into the producer, a poker, means for actuating the same, a plow co-operating therewith to smooth the fuel bed after it has been subjected to the action of the poker, and means controlled by said plow for regulating the amount of fuel fed to the producer, substantially as described.

10. A gas producer having in combination a body portion, a cover, means for producing a relative movement between the body and cover, a poker, and means for causing the poker to travel in spirals, each spiral extending substantially entirely around the fuel bed, substantially as described.

11. A gas producer having in combination a body portion, a cover, means for producing a relative movement between the body and cover, a poker, means for causing the poker to travel in spirals, each spiral extending substantially entirely around the fuel bed, and means for automatically reversing the direction of travel of the poker, substantially as described.

12. A gas producer having in combination a body portion, a cover, means for rotating one of said portions relative to the other, a poker eccentrically mounted on the cover and extending down into the body portion, its lower end being movable in a spiral, and means for operating the poker, substantially as described.

13. A gas producer having in combination a body portion, a cover, means for rotating one of said portions relative to the other, a poker eccentrically mounted on the cover and extending down into the body portion, its lower end being movable in a spiral, and means for operating the poker in opposite directions, substantially as described.

14. A gas producer having in combination a body portion, a cover, means for producing relative movement between the body portion and cover, a poker swingingly mounted on the cover, said poker having its lower end bent to compress the fuel within the body portion of the producer, and means for swinging said poker in opposite

directions about its longitudinal axis, substantially as described.

65

15. A gas producer having in combination a body portion, a cover, means for producing a relative rotational movement between the body portion and cover, a poker mounted on the cover for swinging movement about its longitudinal axis, means for gradually swinging said poker about its axis during at least one relative rotational movement to cause the same to engage successive portions of the fuel body from the outside to the inside thereof, and means for reversing the movement of said poker to cause the same during at least one complete relative rotational movement to engage successive portions of the fuel body from the inside to the outside thereof, substantially as described.

70

16. A gas producer having in combination a body portion, a cover, means for producing a relative rotational movement between the body portion and cover, a poker swingingly mounted on the cover, a segmental gear secured to said poker, means engaging said gear for swinging the poker about its longitudinal axis, and means for reversing the direction of swinging movement of said poker, substantially as described.

80

17. A gas producer having in combination a body portion, a cover, means for producing a relative rotational movement between the body portion and cover, a poker swingingly mounted on the cover, a segmental gear secured to said poker, means engaging said gear for swinging the poker about its longitudinal axis, and means for automatically reversing the direction of swinging movement of said poker, substantially as described.

90

18. A gas producer having in combination a body portion, a cover, means for producing a relative rotational movement between the body portion and cover, a poker swingingly mounted on the cover, a segmental gear secured to said poker, means engaging said gear for swinging the poker about its longitudinal axis, and means for automatically reversing the direction of swinging movement of said poker, substantially as described.

95

19. A gas producer having in combination a body portion, a cover, means for producing a relative rotational movement between the body portion and cover, a poker swingingly mounted on the cover, and means alternately effective for producing opposite swinging movement of said poker about the longitudinal axis thereof, substantially as described.

100

20. A gas producer having in combination a body portion, a cover, means for producing a relative rotational movement between the body portion and cover, a poker swingingly mounted on the cover, and means alternately effective for producing opposite swinging movement of said poker about the longitudinal axis thereof, each of said swinging movements extending through less than a complete circle, substantially as described.

110

In testimony whereof I have hereunto set my hand.

REINHARDT DAAE.
